Application November 13, 1933, Serial No. 697,710
In Germany March 30, 1933

16 Claims. (Cl. 235—79)

This invention refers to calculating machines of the key-board-type. The invention may, for instance, be applied to the so called pin-wheel or Odhner-machines and also to the Thomas-machines, Baldwin-machines etc.

A chief object of this invention is to provide for a simple and efficient rapid-acting coupling between a driving motor and the rotary mechanism carrying out the calculating operations.

10 Said rotary mechanism or actuator is generally identical with the setting members or secured to them but separate setting members are sometimes used. A further object of the invention is to make it possible to operate the machine safely and efficiently at a high speed.

15 A further object of the invention is to render it possible to operate the machine both as a multiplying machine and as an adding machine at a high velocity in both cases.

20 A further object of this invention is to adapt the machine for addition-subtraction and for multiplication-division, respectively, by adjusting one single member.

25 A further object of this invention is to render it possible to have, at the choice of the operator, the zeroizing either effected automatically after each stroke or revolution of the machine or effected by hand only after a desired number of strokes or revolutions.

30 A further object of this invention is to cause the machine itself to zeroize or clear the setting mechanism upon release.

35 A further object of this invention is to render it possible to stop the rotary parts safely from high speeds of operations.

Two embodiments of the invention are shown in the annexed drawings.

Fig. 1 is an end view of the machine from its right side, the end wall carrying the shafts having been removed, and shows some parts in section.

40 Figs. 2—6 are cross-sectional views taken on the lines indicated by the corresponding Roman numbers in Fig. 1.

45 Fig. 7 is a cross-sectional view taken on the line VII—VII in Fig. 6.

Fig. 8 is a cross-sectional view taken on the line VIII—VIII in Fig. 7.

50 Fig. 9 is a cross-sectional view taken on the line IX—IX in Fig. 5 and shows an end view of the zeroizing device proper for the setting device.

Fig. 10 is a detail view of the tens transfer mechanism of the highest digit of the results counter or register.

Fig. 11 is a top view of the machine, some parts being broken away; and

Fig. 12 is a detail view of a modified embodiment.

The machine illustrated is substantially of the type shown in the U. S. patent application Serial No. 431,872 for "Improvements in calculating machines" filed by Karl Viktor Rudin on the 27th of February 1930, and also shown and described in the German Patent No. 535,576 and in the U. S. Patent No. 1,927,771, and it is, therefore, not necessary to describe the same here in detail. The machine is of that general type which is termed Odhner or pin-wheel-machine and has rotor discs provided with teeth slidable in radial or axial direction and adapted to be set by means of a curve slot disc or a setting ring. The invention is, however, not limited to that particular type of calculating machines.

Referring now to the drawings, 5 indicates a main operating or actuator supporting shaft rotatably journaled in the machine frame A. On said shaft a carriage 4 is slidably mounted and carries a setting device or actuator comprising a number of pin wheels 4a of the Odhner-type, as shown in detail in the patents and the patent application cited above. For effecting the calculating operations the main shaft 5 is rotated in either direction (+ or — direction, as the case may be). The pin-wheels are set by means of ten setting keys B, for instance, in the manner set forth by the patents and the patent application just cited.

In addition to said ten setting keys B and the tabulator keys C the machine has two (revolution) keys 1 and 2 marked + and —, and also a zeroizing key 3 (Figs. 1 and 11). On the front side of the machine, that is the side facing the operator, a movable lever 7 is arranged, which is adjustable to two positions, indicated in Fig. 1 by full lines and dash-and-dot lines, respectively. The lower (full line) position is indicated by "addition" and "subtraction" on the casing of the machine, while the upper (dash-and-dot line) position is marked "multiplication" and "division". When the lever 7 is in its lower position the setting mechanism or actuator of the machine is zeroized automatically after each stroke of the machine, while such zeroizing is effected only when the zeroizing key 3 is manipulated by hand, if said lever is in its upper position. The results register D and the quotient register or revolutions counter E are zeroized in well-known manner, for instance, by hand by means of levers F, G, wing-nuts, handles or the like.

In this specification the expressions "front", "back", "right", "left", "upwards" and "downwards" are used as they appear to an operator sitting at the key board of the machine, unless 5 otherwise stated.

An electric motor H drives via a gear K a shaft 8 (Figs. 1 and 11) having a toothed wheel L meshing with a toothed wheel 11 on a shaft 9 to drive the latter. Because the motor H has 10 only one direction of rotation, the shaft 9 always will rotate in the same direction when the motor contacts 35 are closed. To said shaft 9 two toothed wheels 10 and 11 are secured, of which the wheel 11 directly drives a toothed wheel 12, 15 while the wheel 10 drives a toothed wheel 13 via an intermediate wheel 14, the two toothed wheels 12 and 13 being thus rotated in opposite directions (+ and - directions). They are loosely journalled on a shaft 15 on both sides of a coupling arm 16 secured to said shaft. On a pin 18 on said arm 16 a coupling ratchet or pawl 17 is swingable in the axial direction of said shaft 15 (see especially Fig. 6). The wheels 12 and 13 have one projection 20, 21 each and the 25 pawl 17, while in its normal middle position, is out of engagement with said projections 20, 21. If, however, said pawl is swung axially it will engage one of those projections and then couple the corresponding toothed wheel 12 or 13 to the shaft 15, which is thus caused to rotate in the corresponding direction. Said rotation is transmitted from the toothed wheel 22 secured to the shaft 15 via wheels 23, 24 (Fig. 1) to a toothed wheel 25 secured to the main operating 30 shaft 5. Consequently, the setting device or actuator 4, 4a is caused to rotate in the corresponding direction. In the drawings the directions of rotation for + operations (addition and multiplication) and for - operations (subtraction 35 and division) are indicated by arrows marked accordingly.

To the shaft 9 a curve slot disc or cylinder 26 (Figs. 1 and 5) is also secured whose curve slot is always engaged by a pin 27 on one end of a lever 45 29 rotatably journalled on the pin 28, said lever being thus moved with a rocking motion to and fro when the motor H runs. At its other or front end said lever 29 carries a slide 30 pressed downwards by a spring 31 (Figs. 1 and 4). The 50 slide 30 is slidably journalled on the lever 29 by means of pins 30a and slots.

On a stationary shaft 33 a triangular member 34 is secured which is rocked by the keys 1 and 2, if either of them is depressed (Fig. 1). Then 55 the lever 34 closes the contacts 35 for the electric current to the motor H and the motor is started, causing the wheels 12 and 13 to be rotated in opposite directions and the slide 30 to be reciprocated or rocked in the axial direction of shaft 15. If the key 1 or 2 is further depressed its projection 91 or 92, respectively, will abut against a sliding or push rod 36 or 37, that is, if the + key 1 is depressed, the sliding rod 36 is pressed upwards by projection 91 and if the 60 - key 2 is depressed the sliding rod 37 is pressed upwards by projection 92 (see especially Fig. 4). The rod which is thus lifted enters the path of the reciprocating slide 30 and is moved laterally by the same to the corresponding side. Thus, in 65 Fig. 4 the rod 36 is moved to the left and the rod 37 to the right, is lifted by the keys 1, 2. If the slide 30 should be just above the rod 36 or 37, when the latter is lifted, said rod will first lift the slide, which is then at the beginning of its 70 next axial stroke pressed down laterally of the 75

lifted rod by the spring 31 and thereafter moves the latter sideways, as just mentioned. A bent or U-shaped guide member 39 is connected with said rods 36, 37 by means of pins 38; sliding in vertical oblong slots in the rods 36, 37. (Figs. 1, 4, 7 and 8). If one of said rods is moved laterally, it will also move the member 39 laterally, accordingly. Said member 39 has an arcuate portion formed with a slot or opening 40 of the shape shown in Fig. 8 and the outer narrow end 11a of the pawl 17, during a part of its rotation will enter said slot 40. If said guide member 39 has been moved laterally (Fig. 8) from its normal middle position in the manner just indicated the pawl 17, during its next revolution will be rocked a corresponding distance laterally, that is, in the axial direction in relation to the shaft 15, to thus couple the corresponding toothed wheel 12 or 13 to the shaft 15, as mentioned above (Fig. 6). Thus, the + key 1 originates a + 20 rotation, when depressed, and the - key 2 a - rotation.

The guide member 39 has a spring 41 supported on a fixed shaft and engaging ears 39a on member 39 (Figs. 7 and 8) for restoring said member to its normal middle position. When the corresponding sliding rod 36 or 37 again is returned to its lowermost position by one of the restoring springs 42 (Fig. 1), when the depressed key 1 or 2 is released, the member 39 is restored to its normal middle position and returns the pawl 17 to its normal position at its next rotation, by means of the guiding slot 40.

Two pull rods 43, 44 are articulately connected with respective locking arms 45, 46 and are 35 pressed upwards by springs 47.

If either of the keys 1 or 2 is depressed, the pull rod 43 or 44, as the case may be, is drawn upwards by the corresponding spring 47 (Figs. 1 and 4) and said rod then swings the locking arm 45 or 46, as the case may be, (Figs. 1, 6 and 8) upwards to engage the notches 45a or 46a in the lower corners of member 39, thus causing the member 39 to be locked by the arm 45 or 46, as the case may be, in the extreme position of its lateral motion which was originated by the depression of said key. When the key 1 or 2 is released again, the rod 43 or 44 is drawn downwards by its pin 48 or 49 (Figs. 1 and 4) engaging the key, so that the locking 50 of the member 39 is released (Fig. 8).

The restoring springs 51 of the keys 1, 2 have to overcome the pull of the springs 47, when the keys are released and for this reason the springs 51 must be stronger than the springs 47.

When the pawl 17, rocked laterally by the guiding slot 40 of the member 39, continues its rotation said pawl comes out of engagement with said slot but will then be guided on the corresponding side of a circular guiding rail 50 (Figs. 1 and 6) and is thereby maintained in correct engagement with the projection 20 or 21, as the case may be. As seen from Fig. 1, said guiding rail 50 embraces such a part of a revolution (of 360°) that the pawl 17 will enter the slot 40 60 just as it leaves the guide 50.

When the pawl 17 is restored to its normal middle position by the guide slot 40 it is disengaged from the projection 20 or 21, as the case may be, and the shaft 15 and the pin wheels 4 will stop, while the toothed wheels 12 and 13 70 continue their rotation (running light) until the motor current is broken by the contacts 35.

To lock the actuator or pin wheel rotor 4, 4a against rotation on the shaft 5 in its position of 75

rest a disc 52 (Figs. 1, 2 and 3) is secured to said shaft 5 and provided with a lateral projection or stud 53 arrested between two pawls 54, 55 in said position of rest. Those pawls are rotatably 5 journalled each on one of the arms 57, 58 which are swingable on the stationary shaft 56. A tension spring 59 pulls said arms against a stationary pin 59a and, when at the end of a rotary motion of the pin wheel rotor 4, 4a one of the pawls 54 10 or 55 strikes upon the stud 53 to stop said rotor, the spring 59 absorbs the shock. A spring 60 presses the pawls 54 and 55 to engage the projection 53.

When upon depression of a key 1 or 2 the 15 guide member 39 is moved from its normal position said member via the corresponding pin 38 depresses one end of a lever 61 (Figs. 1, 3 and 4) pivoted at 61a, so as to cause the opposite end of said lever to engage the pins 62 secured to the 20 pawls 54, 55 and to lift the latter out of engagement with the stud 53. Thus, the locking of the setting device 4, 4a is released before the rotary motion begins.

When thereafter the key 1 or 2 is released and 25 consequently the corresponding rod 36 or 37 returns to its lowermost position, the lever 61 is also released and the pawls 54, 55 are restored by the spring 60 to their locking position to stop the pin wheel rotor 4, 4a.

30 As shown in Fig. 1 the pawls 54, 55 have one front nose or point 150 and one back nose or point 151 each. If the stud 53, in its rotation, should pass by the front or outer nose of the corresponding pawl, before said nose has returned 35 to its locking position, the stud 53 will be engaged by the other (back or inner) nose of the same pawl and will bounce back, thus rendering it possible for the front nose of the same pawl to snap in to engage the stud 53. Consequently, 40 the pin wheel rotor will always be stopped in its correct position of rest as shown in Fig. 1.

To prevent the motor current from being broken during the rotation of the pin wheel rotor a lever 19 is provided pressed by a spring 200 to 45 engage a curve on the disc 52. When the actuator 4, 4a is off-normal, said curve will rock the lever 19 to keep the contacts 35 closed via the member 34 until the pin wheel rotor has returned to its position of rest shown in Fig. 1. Then one 50 end of the lever 19 enters a lower part of the curve of the disc 52 and does not longer prevent a breaking of the contacts 35.

The coupling members for zeroizing or clearing the setting device are as follows:

55 The main operating shaft 9 drives, via the toothed wheel 10, a toothed wheel 63 secured to a shaft 64 (Figs. 1 and 5). To said shaft a projection or tooth 65 is secured. Furthermore, a toothed wheel 66 is loosely journalled on said 60 shaft and provided with a flange 67 (Fig. 5) riveted thereto and on said flange a radially swing- 65 ing pawl 68 is journalled on the pin 68a (Fig. 1) and urged by a tension spring 69 toward the tooth 65. Said pawl is, however, normally kept 70 out of engagement with the tooth 65 by a lever 70 pivoted on a stationary shaft 71 (Figs. 1 and 6). A tension spring 72 urges the projection end or point 70a of said lever 70 to engage a 75 curve disc 73 (Figs. 1 and 5) secured on a shaft 74 which also carries a toothed wheel 75 meshing with the toothed wheel 66.

If the zeroizing key 3 is actuated, for instance, by hand, the back end of said key will engage a pin 76 secured to the lever 70 to rock said lever 75 out of engagement with the pawl 68. Said lever

will simultaneously depress the pin 81 secured to the lever 34 to close the contacts 35. The spring 69 then draws the pawl 68 to engage the tooth 65, thus causing the wheel 66 to be coupled with the shaft 64 now driven by the motor H. 5 The wheel 66 will consequently drive the toothed wheel 75 until the pawl 68, after one revolution of the shaft 74, is again disengaged by the lever 70, which meanwhile has been restored to its normal position by point 70a moving into the depression in disc 73. Thus, also the lever 34 is freed and the motor current is broken by the contacts 35.

During the rotation of the wheel 75 thus brought about the setting device or actuator is 15 zeroized as follows:

The shaft 74 (Figs. 1, 5 and 9) is also provided with a curve disc or cam 77. A roller 79 on a lever 78 engages said disc, and when the latter is rotated the lever 78 will be rocked as indicated 20 in dash-and-dot lines in Fig. 9. A pull rod 80 articulately connected with the lever 78 will actuate zeroizing members of any well-known or suitable construction when said lever is rocked. Thus, the other end of the lever 80 may be 25 articulately connected, for instance, with the arm 29 or the zeroizing lever 32 of the setting device as shown in the U. S. Patent No. 1,927,771. Thus, the setting device (the pin wheels) is 30 restored to its zero position and the pin wheel rotor slides back to its position of rest, as described in the U. S. Patent No. 1,927,771 and also in the U. S. Patent application Serial No. 431,872 (German Patent No. 535,576).

Each time the key 3 in Fig. 1 is actuated the 35 setting device or actuator will consequently be zeroized.

In the very beginning of the rotation of the wheel 75 the point 70a of the lever 70 will ride up on a higher part of the curve disc 73, thus 40 preventing the lever 70 from being restored to that position in which it disengages the pawl 68, before the curve disc 73 has completed one full revolution. Consequently, the end 70b of the lever 70 engaging the pin 81 of the lever 34 45 keeps the latter depressed and the contacts 35 closed until the zeroizing procedure is completed. In the embodiment shown the toothed wheel 66 has only half of the number of teeth of the toothed wheel 75 and consequently the 50 shaft 64 makes two revolutions for each revolution of the shaft 74 necessary to cause the curve disc 73 to effect a complete zeroizing of the setting device 4, 4a.

The zeroizing operation effected by the motor 55 upon manipulation of the key 3 by hand is the zeroizing necessary for multiplication and division. For addition and subtraction the setting device 4, 4a should be automatically zeroized 60 after each stroke or revolution of the machine. For this purpose the following device is provided:

To the adjustable lever 7 mentioned above a pin 82 is secured (Figs. 1 and 2) which in the lowermost position (addition, subtraction) of said 65 lever 7 engages a point or nose 83a of the lever 83, the latter being rotatable on a pin 84 secured to the zeroizing key 3. If either of the keys 1 and 2 is depressed the disc 52 will rotate, as described above, and two pawls 85, 86 rotatably 70 journalled thereon will then strike the point 83b of the lever 83. Springs 87 normally press said pawls against pins 88, 89 (Fig. 1). If the disc 52 rotates, for instance, in the + direction in Fig. 1 (counter-clock-wise) the pawl 85 will first 75

strike on the point 83b but said pawl will be rocked aside and stress the corresponding spring 87 which will afterwards restore it to engage the pin 88. At the end of this rotary motion 5 of the disc 52, when the calculating operation (addition) brought about by the rotation of the pin wheels 4 has been transferred to the results counters, the pawl 86 strikes the point 83b. The pin 89 prevents said pawl from being rocked 10 aside, thus causing said pawl to swing the upper end 83b of the lever 83 aside. Because said point 83a engages the pin 82 the lever 83 will then fulcrum on the pin 82 and the lower end thereof swings and moves the zeroizing key 3 15 inwards to cause a zeroizing operation automatically, as described above.

If, on the contrary, said disc 52 rotates in the direction (clockwise in Fig. 1) the pawl 85, in a similar manner, swings the lever 83 automatically to initiate the zeroizing operation, after 20 the pin wheel rotor 4, 4a has completed its subtractive operation in the results counter D.

Because such automatic release of a zeroizing operation might not begin, until after the calculating operation is completed and the pin wheel rotor 4, 4a thus is near the end of its rotary motion, the pawls 54, 55 have only a very short time for snapping in to stop said rotor. The double points of said ratchets and the 30 bouncing operation effected thereby is then very important to arrest the rotor in due time and thus to prevent miscalculations and faults.

As is shown in Figs. 1 and 4, the lower ends of the rods 36, 37 are slidable in a release slide 90, engaged by a projection 3a of the zeroizing key 3. When said key 3 is moved backwards, that is, to the right in Fig. 1, to initiate the zeroizing operation, the slide 90 and consequently also the lower ends of the rods 36, 37 will be 40 pushed backwards and disengaged from the projections 91, 92 of the keys 1, 2. Consequently, even if either of the revolutions keys 1, 2 should be kept depressed, after the key 3 has been actuated, the springs 42 will draw the corresponding rod 36 or 37 downwards, because the lower end of said rod will then pass laterally of the projection 91 or 92 of the key 1 or 2, as the case may be. Simultaneously the pin 90b secured to an extension of the slide 90 will strike 50 against one end of the locking arm 45 or 46 if the same is in locking position, thus unlocking the member 39, so that the actuator 4, 4a may be disconnected from the motor H, as described above and be stopped and locked in its position 55 of rest by the spring-actuated pawls 54, 55. After each stroke or revolution of the machine in adding or subtracting operations the setting and actuating device is consequently automatically zeroized and, even if either of the keys 1 or 2 is kept depressed said device will be 60 stopped in its position of rest (home position) and locked therein after every stroke of the machine, that is, every time an item has been added or subtracted.

If on the contrary the lever 7 is adjusted to its uppermost position (multiplication, division) shown in dash-and-dot lines in Fig. 1, the spring 93 withdraws the lever 83 from the path of the 70 pawls 85, 86 and the actuator 4, 4a will not be zeroized until the zeroizing key 3 is manipulated by hand. In this case the actuator 4, 4a also continues its rotation for (multiplication and division), because the projection 91, 92 keeps the 75 rod 36 or 37, as the case may be, in its uppermost

position until the key 1 or 2, as the case may be, is released or the key 3 actuated. For multiplication and division several revolutions of the pin wheel rotor 4, 4a (for each digit) are generally necessary and this is consequently attained in 5 the most rapid and simple manner.

The slide 90 is further provided with a projection 90a engaged by a pin 94 secured to a lever 95 rotatable on the shaft 71 (Figs. 1, 5 and 6). The opposite end of said lever engages a 10 curve 96 on the shaft 74 and thus prevents the release slide 90 from returning to its position of rest under the action of the spring 97, until the zeroizing of the pin wheel rotor 4, 4a is completed. Consequently, said pin wheel rotor will 15 remain in its position of rest locked against rotation, until the pin wheels are completely zeroized.

Fig. 10 shows the last (highest) tens transfers pawl or hammer 100 of the results counter D, 20 that is the tens transfers pawl for the figure or counting wheel 101 of the highest digit of said counter. If in operations of division the capacity of the results counter is exceeded, that is, if the pawl 100 is rocked and the figure wheels of at 25 least the highest digits of said counter show the number "9", said pawl simultaneously lifts one end 152 of a double or bell crank lever 102 (Figs. 1, 5 and 10) upwards. The other end 153 of said lever will swing the lever 104 rotatable on the pin 103 and the opposite end of said lever will then strike against a pin 105 on the release slide 90 to push the latter backwards, that is, to the right in Fig. 1. In the manner described above 30 the rod 36 or 37 is then released from the projection 91 or 92 and the motor H is disconnected from the actuator 4, 4a. Consequently, if the capacity of the results counter D is exceeded in 35 divisional operations, the machine is automatically stopped. By depressing the + key 1 the 40 actuator is then rotated one revolution in the opposite direction (that is, in the + direction) and by means of the tabulator keys C the pin wheel carriage 4 is moved to the next (lower) digit and the division is continued in the usual manner. 45 By means of this device the division is considerably simplified and facilitated and may be carried out very rapidly and mechanically.

The use of the double pointed pawls 54, 55 is 50 also very important to secure a rapid and correct action in stopping the rotation of the actuator upon the automatic release of the zeroizing operation from the last tens transfers pawl 100 of the results counter D because also in this case the release may be effected immediately before 55 the completion of a revolution of the pin wheel rotor, because the tens transfer is often effected immediately before the calculating operation is completed.

The following may be mentioned about the 60 speeds of rotation of the toothed wheels and shafts:

In the embodiment shown the driving shaft 9 with the toothed wheels 10 and 11 has the same speed of rotation, that is, number of revolutions, 65 as the wheels 12, 13 and 63, and for each revolution of the shaft 9 the pin wheels 4a will rotate one revolution. In addition and subtraction operations the actuator 4, 4a will first complete one revolution and thereafter the shaft 64 will 70 make two revolutions for the automatic zeroizing. The addition or subtraction of an item will thus require three times the time necessary for one revolution of the pin wheels in operations of multiplication and division. But if the machine 75

is well and correctly constructed the total time for adding or subtracting an item is very short and about as long as the corresponding time for the same operation in the common adding machines.

5 For adjusting the machine from addition-subtraction to multiplication-division, and vice versa, only a short displacement of the lever 1 is necessary.

10 It is however, to be observed that it is not necessary for the shaft 64 to make two revolutions for a zeroizing operation, but such operation may be effected by one or, for instance, three revolutions of said shaft. It is only the permissible 15 maximum strains of the material that are decisive for the maximum speed of said shaft and of the whole zeroizing operation.

It is evident that the latching and locking devices generally used in calculating machines 20 may be used in the machine in accordance with this invention, for instance, interlocking means for preventing simultaneous depression of the two keys 1 and 2 or for preventing the zeroizing key from being actuated during the rotation of the 25 pin wheels etc. Such devices are well-known in the art. The machine and the zeroizing members may be of any other suitable construction different from those described in the U. S. Patent No. 1,927,771 and the U. S. patent application Serial No. 431,872 German Patent No. 535,576.

30 In the modified embodiment shown in Fig. 12, four pawls 54a, 54b, 55a, 55b are substituted for the double pointed pawls 54, 55 of Fig. 1, that is, each double pointed pawl is replaced by one long 35 pawl 54a or 55a and one short pawl 54b or 55b, each having only one point as usual. The pawls 54a and 54b are, preferably, journaled on the same pin 201, and the pawls 55a and 55b on the same pin 202 and are independent of each other. 40 The long pawls 54a, 55a are actuated by a common spring 60a and the short pawls 54b, 55b by a common spring 60b. In other respects this embodiment is similar to that shown in Fig. 1 and corresponding parts carry the same reference characters. When said pawls 54a, 54b, 55a, 45 55b are released by the lever 61 acting on the pins 66 they are all four lifted simultaneously. In certain cases such independent pawls are preferred to the double pointed pawls.

50 While we have shown and described two more or less specific embodiments of our invention, it is to be understood that this has been done for purposes of illustration only, as required by the patent statutes, and these embodiments are not 55 to be considered as in any manner limiting the scope of our invention, which is to be determined by the appended claims viewed in the light of the prior art. Moreover, certain subject matter described but not claimed herein, is claimed in 60 our copending divisional application Serial No. 103,261.

What we claim is:—

1. In a calculating machine having a unidirectional motor, an actuator adapted to be rotated in either direction and a shaft operative to rotate said actuator; a releasable and reversible transmission between said motor and said shaft, zeroizing mechanism for said actuator, a pair of pawls on said actuator, stops on said actuator for said pawls, resilient means engaging said pawls against said stops, and an adjustable member movable into the path of said pawls, said member being movable by said pawls to render said zeroizing mechanism operative.

75 2. In a calculating machine having a unidi-

rectional motor, an actuator adapted to be rotated in either direction and a shaft operative to rotate said actuator; a releasable and reversible transmission between said motor and said shaft, zeroizing mechanism for said actuator, a second 5 releasable transmission between said motor and said zeroizing mechanism, a pair of pawls on said actuator, stops on said actuator for said pawls, resilient means urging said pawls against said stops, and a member operatively connected with said second transmission and adjustable into and out of the path of said pawls.

3. In a calculating machine having a unidirectional motor, an actuator adapted to be rotated in either direction and a shaft operative to 15 rotate said actuator; a releasable and reversible transmission between said motor and said shaft, zeroizing mechanism for said actuator, a pair of pawls on said actuator, an operating lever connected to said zeroizing mechanism, a movable 20 fulcrum for said lever, and means for moving said fulcrum to move said lever into and out of the path of said pawls.

4. In a calculating machine having a unidirectional motor, an actuator adapted to be rotated 25 in either direction, and a shaft operative to rotate said actuator; two gears loosely journaled on said shaft and rotated in opposite directions by said motor, projections on said gears, a pawl mounted for rotation with said shaft between 30 said gears, said pawl being pivotally mounted on said shaft so as to move into and out of the paths of said projections, means including rods movable for pivoting said pawl, keys for moving said rods, zeroizing mechanism for said actuator, an engageable and releasable coupling between said motor and said zeroizing mechanism, and means for moving said rods to disengage 35 said pawl from said projections when said coupling is engaged.

40 5. In a calculating machine having a unidirectional motor, an actuator adapted to be rotated in either direction, and a shaft operative to rotate said actuator; two gears loosely journaled on said shaft and rotated in opposite directions by said motor, projections on said gears, a pawl mounted for rotation with said shaft between 45 said gears, said pawl being pivotally mounted on said shaft so as to move into and out of the paths of said projections, means including rods movable for pivoting said pawl, keys for moving said rods, zeroizing mechanism for said actuator, an engageable and releasable coupling between said motor and said zeroizing mechanism, and a slidably mounted member for moving said rods to disengage said pawl from 50 said projections when said coupling is engaged.

6. In a calculating machine having a unidirectional motor, an actuator adapted to be rotated in either direction, and a shaft operative to rotate said actuator; two gears loosely journaled on said shaft and rotated in opposite directions by said motor, projections on said gears, a pawl mounted for rotation with said shaft between 65 said gears, said pawl being pivotally mounted on said shaft so as to move into and out of the paths of said projections, means including rods movable for pivoting said pawl, keys for moving said rods, zeroizing mechanism for said actuator, an engageable and releasable coupling between 70 said motor and said zeroizing mechanism, a key for operating said coupling, and a member operatively connected to said key and said rods for moving said rods to disengage said pawl from 75 said projections when said key is actuated.

7. In a calculating machine having a unidirectional motor, an actuator adapted to be rotated in either direction, and a shaft operative to rotate said actuator; a releasable and reversible transmission between said motor and said shaft including a coupling and reversing pawl, means including rods movable to move said pawl, a slidable member permanently in engagement with said rods, numeral wheels arranged to be actuated by said actuator, and tens transfer pawls for said numeral wheels, the tens transfer pawl for the highest digit of said numeral wheel being connected with said slidable member, whereby actuation of the last mentioned pawl causes said slidable member to move said rods to actuate said coupling and reversing pawl to release said transmission.
8. In a calculating machine having a unidirectional motor, an actuator adapted to be rotated in either direction, and a shaft operative to rotate said actuator; a releasable and reversible transmission between said motor and said shaft including a coupling and reversing pawl, an arcuate member displaceable for moving said pawl, rods movable to displace said arcuate member, a slidable member permanently in engagement with said rods, zeroizing mechanism for said actuator, a key movable to initiate operation of said zeroizing mechanism and to engage said slidable member, and locking means for said arcuate member, said locking means being releasable by said slidable member.
9. In a calculating machine having a unidirectional motor, an actuator having a normal position of rest and adapted to be rotated in either direction, and a shaft operative to rotate said actuator; a starting and stopping switch for said motor, a releasable and reversible transmission between said motor and said shaft, a cam disc secured to said shaft, and a cam lever permanently engaging said disc and operable to maintain said switch closed so long as said actuator is out of its normal position of rest.
10. In a calculating machine having a unidirectional motor, an actuator adapted to be rotated in either direction, and a shaft operative to rotate said actuator; a starting and stopping switch for said motor, a releasable and reversible transmission between said motor and said shaft, zeroizing mechanism for said actuator, a releasable coupling between said motor and said zeroizing mechanism, means for engaging said coupling, means for maintaining said switch closed during engagement of said coupling, and means for maintaining said transmission released during engagement of said coupling.
11. In a calculating machine having a unidirectional motor, an actuator adapted to be rotated in either direction and a shaft operative to rotate said actuator; a releasable and reversible transmission between said motor and said shaft, zeroizing mechanism for said actuator, a releasable coupling between said motor and said zeroizing mechanism, means for engaging said coupling, an electric switch for starting and stopping said motor, a cam disc driven by said coupling, a cam lever permanently in engagement with said cam disc and operatively connected to said switch, said cam disc and cam lever being operable to maintain said switch closed during engagement of said coupling, and means for maintaining said transmission released during engagement of said coupling.
12. In a calculating machine having a unidirectional motor, an actuator adapted to be rotated in either direction and a shaft operative to rotate said actuator; a releasable and reversible transmission between said motor and said shaft, said actuator including a shaft, a carriage axially movable on the actuator shaft, rotary actuating elements on said carriage and a disc having a projection thereon secured to said actuator shaft, a pair of pivotally mounted arms, a spring between said arms, and a ratchet member mounted on each of said arms and arranged to engage and release said projection.
13. In a calculating machine having a unidirectional electric motor, an actuator adapted to be rotated in either direction, a shaft operative to rotate said actuator, two gears loosely journaled on said shaft and rotated in opposite directions by said motor, projections on said gears, a pawl mounted for rotation with said shaft between said gears, said pawls being pivotally mounted on said shaft so as to move into and out of the paths of said projections, a slotted member movable for pivoting said pawl, keys for moving said slotted member, a zeroizing mechanism for said actuator, an engageable and releasable coupling between said motor and said zeroizing mechanism, means for moving said slotted member to disengage said pawls from said projections when said coupling is engaged, and positive means for maintaining said switch closed when said coupling is engaged.
14. In a calculating machine having a motor, an actuator adapted to be rotated by said motor, a starting and stopping switch for said motor, a zeroizing mechanism for said actuator, a releasable coupling between said motor and said zeroizing mechanism, means for engaging said coupling, and positively controlled means for maintaining said switch closed during engagement of said coupling.
15. In a calculating machine having a unidirectional motor, an actuator adapted to be rotated in either direction, a zeroizing mechanism for said actuator, a releasable coupling between said motor and said zeroizing mechanism, an electric switch for starting and stopping said motor, a cam disc driven by said coupling, and a cam lever permanently in engagement with said cam disc and operatively connected to said switch, said cam disc and cam lever being operable to maintain said switch closed during engagement of said coupling.
16. In a calculating machine having a unidirectional motor, an actuator having a normal position of rest and adapted to be rotated in either direction, a shaft operative to rotate said actuator, a starting and stopping switch for said motor, a releasable and reversible transmission between said motor and said shaft, a zeroizing mechanism for said actuator, a releasable coupling between said motor and said zeroizing mechanism, a rockable member engaging said switch to actuate and release the same, a cam disc secured to said shaft, another cam disc driven by said coupling, and cam levers permanently engaging said discs and said rockable member and operable to maintain said switch closed so long as either said actuator or said coupling is actuated.
